WALLET

Ludwig S. Schlessinger, New York, N.Y., assignor to
Bond Street Ltd., New York, N.Y., a corporation of
New York

Filed Nov. 20, 1964, Ser. No. 82,719

Term of patent 14 years

(Cl. D87—3)

FIG. 1 is a front perspective view of a wallet showing my new design, in closed condition;

FIG. 2 is a similar view thereof, but showing the wallet in open condition; and

FIG. 3 is a view similar to FIG. 2, but also showing the pass case section of the wallet opened, pass leaves being shown in broken lines for illustrative purposes only.

The rear of the wallet, not shown, is substantially similar to the front as shown in FIG. 1.

The characteristic feature of my design resides in the combination, on the wallet disclosed, of the stepped-down top edges of the currency pocket walls together with a hinged central section which presents a substantially symmetrical appearance to the inside faces of the wallet when folded to either side thereof, all as shown.

I claim:

The ornamental design for a wallet, as shown and described.
